UNITED STATES PATENT OFFICE.

CHARLES FISHER, OF MANITOWOC, WISCONSIN, ASSIGNOR TO THE INTERNATIONAL STORE SERVICE COMPANY, OF SAME PLACE.

CASH-CARRIER.

SPECIFICATION forming part of Letters Patent No. 309,704, dated December 23, 1884.

Application filed July 18, 1884. (No model.)

To all whom it may concern:

Be it known that I, CHARLES FISHER, of Manitowoc, in the county of Manitowoc and State of Wisconsin, have invented certain new and useful Improvements in Cash-Carriers; and I do hereby declare the following to be a full, clear, and exact description of the invention, such as will enable others skilled in the art to which it pertains to make and use the same.

My invention relates to cash-carriers for use in stores, &c., the object being to simplify and improve mechanism of this character, and thus insure readiness and durability of the parts in use and economy in construction.

The invention consists in combining with a track consisting of a single rail or strip a carrier formed with a central annular groove, and parallel guard-wires for supporting the carrier upon the track.

The invention further consists in combining with the track of a cash-carrier system a switch-rod adapted to yield both vertically and horizontally.

25 The invention further consists in combining with the track a pivoted drop and means for locking and unlocking said drop.

The invention further consists in combining with the elevator of a cash-carrier system a cage formed with an open side and provided with a spring-guard.

The invention also consists in certain details and combinations of devices, hereinafter fully described, and pointed out in the claims.

35 In the accompanying drawings, Figure 1 is an end sectional view of the track and section of cylinder in proper position on the track; Fig. 2, a side view of track and rolling cylinder; Fig. 3, a vertical front or open view 40 of elevator, and view of elevator and track-connections; Fig. 4, a vertical side view of elevator and side view of elevator and track-connections, elevator - switch drop, and track; Fig. 5, a plan view of a switch and the track; Fig. 6, a side view of trap and receiver; Fig. 7, a plan view of a portion of the track and a switch; Fig. 8, a side view of terminal receiver; Fig. 9, a full view of track-suspender bands and guard-supporters; Fig. 10, a sectional view showing the lining of the elevator carriages and receivers.

A represents the main track, B the track-lining, and C the track-guide strip.

D is the cylindrical carrier, formed with an annular groove, E, to correspond with the 55 track-guide strips, and also with the receiver-guide strips, hereinafter mentioned.

F is a cash-receptacle extending through the cylinder, the contents of which are held in place between plates G G, acted upon by 60 push-springs H H', the one, H, being fastened to a stationary cross-bar, I, extending over the receptacle-opening, and the other one, H', to an adjustable pinion-bar, J, operating in catches K K.

This improved carrier is fully described and claimed in my application No. 137,267, filed July 9, 1884; hence I make no claim for said carrier in this case, except as an element of combinations.

65 L is a ceiling-plate; M M, elevator-guide strips; N N, upper and lower elevator-stops; O, the elevator-cage, open at its top to receive the carriers, and open at one side to allow the carriers to roll onto the track. The cage is 70 provided with an inclined floor, P, a spring guard-bail, Q, and stop-pins R R.

S are the upper and lower elevator-cage guides, connected by wires T T or otherwise. The elevator-cage is hoisted by means of cord 75 and pulleys suspended from the ceiling-plate L.

U is the elevator-switch; V, the drop pivoted between standards c by pins W W.

80 X XXX are weights embedded in the drop, 85 which latter engages the stop Y.

Z Z indicate elevator and track-connections.

a, b, and c are supports for the track, and d d are the guard-wires which serve to support 90 the carriers upon the track.

Fig. 5 illustrates a switch-junction of the rails or strips. i is the main track, and f the switch. The frog e permits of the free movement of the carrier upon either the switch or 95 main track.

In Fig. 6 is illustrated the mechanism for operating the drop to deliver the carrier to the adjacent receiver. The drop V is pivoted and weighted, as already described, and its 100 unweighted end is provided with a stop, o, adapted to engage the adjacent end of the track, and also a stop, u, secured to the receiver.

v indicates a band pivoted upon standards 105 v' rising above the track. The under side of

this pivoted band r is provided with a catch, r^2 , connected to one end of a spring, s , whose opposite end is attached to a bracket, r^3 , secured to the under side of the track.

5. q represents a bell-crank lever fulcrumed upon a band, p , which spans the track, and connected by a wire, t , to the pivoted band r . The forward arm of the lever q extends downwardly over the track to be struck by the carrier, which releases the catch r^2 , and the weight of the carrier tilts the drop, whose downward movement is limited by contact with the stop u . The drop is automatically retracted by the weights X .

15. It will be obvious that only the carrier belonging to the receiver adjacent to the drop can operate the latter, as the other carriers will not be of sufficient diameter to strike the lever q .

20. In Fig. 7 is illustrated my improved yielding switch-guide Z^4 . This guide is of curved form, and is suspended above the track by pins 10, which pass through openings formed in supports 11, which span the track. Below 25 these supports 11 are arranged plates 12, formed with elongated openings. The guide thus suspended is capable of yielding both lengthwise and vertically to guide the carrier or carriers, which are of sufficient size to engage it into their proper receiver.

30. The receiver shown in the drawings is provided with check-springs similar to those shown in my pending application, above referred to; hence I make no claim to said springs in this application.

35. The improvements above described contemplate the employment of carriers of different sizes, each station having carriers of different diameter; hence the yielding switch-rod and the pivoted drop are only operated upon by certain of the carriers, and the main track and switches are so arranged with relation to the drops and switch-rods as to insure the proper delivery of the carriers to 40 their respective stations.

45. 18 is a suspender-band, 19 guard-supporter, and C C end sectional views of the track fitted in suspender-band and guard-supporter.

50. The elevator-cages and the receivers are made in such sizes and shapes as to accommodate the cylinders for which they are designated, and if made of sheet metal are lined, as shown in Fig. 10, in which 20 is the sheet metal with a fold in its edge.

55. The lining 23 is cemented or glued on the inside of the cage or receiver, and then over and under the fold, as shown in 21 of Fig. 10, and then the fold is firmly pressed down, as 60 shown in 22 of Fig. 10.

Having fully described my invention, what I claim as new, and desire to secure by Letters Patent, is—

65. 1. In a cash-carrier system, the combination, with a track consisting of a single rail or strip and guard-wires, of a cylindrical car-

rier formed with an annular groove, substantially as set forth.

2. In a cash-carrier system, the combination, with the main track and a switch-track, 70 of a grooved carrier and a switch-guide arranged above the track, to be acted upon by the carrier, substantially as set forth.

3. In a cash-carrier system, the combination, with the main track and a switch-track, 75 of a suspended switch-guide adapted to yield both vertically and longitudinally, substantially as set forth.

4. In a cash-carrier system, the combination, with a single-strip track, of a carrier 80 formed with an annular groove, and a yielding switch-guide suspended above the track to engage the groove of the carrier, substantially as set forth.

5. In a cash-carrier system, the combination, 85 with the track, of a trap or drop forming part of said track and weighted at one end, and a catch device adapted to be operated by the traveling carrier to release the drop, substantially as set forth.

6. The combination, with the track and its pivoted drop, of a pivoted catch-band, and a bell-crank lever provided with a projecting lug, and a wire connecting said band and lever.

90. 7. In a cash-carrier system, the combination, with the track, of an elevator-cage provided with a downwardly-inclined bottom and an open side, and a yielding guard-bail for supporting a carrier within the cage, substantially as set forth.

95. 8. In a cash-carrier system, the combination, with the track, of an elevator-cage having an open side and inclined bottom, a bail consisting of spring-wire, whose ends are 100 coiled around a core secured to the cage, said bail having a projecting lug to engage the track, substantially as set forth.

100. 9. In a cash-carrier system employing a single rail or single-strip track, and a carrier formed with an annular groove, the combination, with the track, of switch-guides adapted to enter the groove of the carrier and guide the latter, substantially as set forth.

105. 10. In a cash-carrier system, the combination, with a weighted drop or trap, of a receiving-case formed with an open side adjacent to said trap, substantially as set forth.

110. 11. The manner herein described of lining a sheet-metal cage for store-service elevators, consisting of gluing or cementing the lining upon the surface of the cage, and concealing the edges of the lining beneath the fold of the metal, substantially as set forth.

115. In testimony whereof I have signed this specification in the presence of two subscribing witnesses.

CHARLES FISHER.
